UNITED STATES PATENT OFFICE.

HAROLD A. MAXFIELD, OF WILKINSBURG, PENNSYLVANIA, ASSIGNOR TO WESTINGHOUSE ELECTRIC & MANUFACTURING COMPANY, A CORPORATION OF PENNSYLVANIA.

VOLTAGE REGULATOR.

Application filed September 23, 1921. Serial No. 502,604.

To all whom it may concern:

Be it known that I, HAROLD A. MAXFIELD, a citizen of the United States, and a resident of Wilkinsburg, in the county of Allegheny and State of Pennsylvania, have invented a new and useful Improvement in Voltage Regulators, of which the following is a specification.

My invention relates to voltage regulators and it has special relation to regulators of the vibratory type.

One object of my invention is to provide a regulator of the above-indicated character which shall include means for insuring the vibratory action of the control magnet thereof.

Another object of my invention is to provide a regulator of the above-indicated character which shall include means controlled from the armature of the regulated machine for varying the flux density of the magnetizable core of the control electromagnet of the regulator.

My invention will be described in connection with the accompanying drawings, wherein—

Figure 1 is a diagrammatic illustration of circuits and apparatus of one embodiment of my invention;

Fig. 2 is a detail view of the flux-varying member of Fig. 1;

Fig. 3 is a diagrammatic illustration of a modification of the regulator of Fig. 1; and

Figs. 4 and 5 illustrate modifications of the regulator of Fig. 3.

The present invention is shown as an automobile voltage regulator but such showing is merely illustrative of the principles involved.

Referring particularly to Figs. 1 and 2, the regulator system includes a generator 1 having an armature winding 2, field-magnet windings 3 and a commutator member 4 mounted upon the armature shaft 5 and having load brushes 6 bearing thereupon. The generator 1 may be connected to any suitable load, here illustrated as a battery 7.

A resistor 8 is included in circuit with the field-magnet windings 3, and a shunt circuit therefor is controlled by electromagnet 9. The electromagnet 9 has an E-shaped magnetizable core 11, upon the central leg of which is wound an energizing coil 12 con-

nected in shunt to the load brushes 6. The magnetizable core 11 has an air gap 17 therein. A movable armature 13 is pivoted at 14 to one leg of the core 11 and is adapted to be attracted against the action of the spring 15. The armature controls the contact members 16 located in the shunt circuit for the resistor 8.

A semi-circular disk 18, best shown in Fig. 2, is mounted upon the armature shaft 5 and is preferably constructed of iron or other magnetizable material. The disk 18 will rotate at the same speed as the generator 1, and in a path which includes the air gap 17. Since there is a predetermined magnetic flux traversing the core 11, producing a predetermined magnetic field in the air gap 17, then, when the disk 18 enters the air gap 17, the flux density of the core 11, and the magnetic field in the air gap 17, will be varied. The variation of the flux density of the core member 11 will vary the pull of the core upon the armature 13, and, since this variation occurs intermittently, the vibratory action of the armature 13 will be insured. Consequently, the efficiency of the vibratory electromagnet is increased, and the contact members of the regulator are maintained clean.

Referring to Fig. 3, the generator 1, having an armature 2 and field-magnet windings 3, and a resistor 8 in circuit therewith, is illustrated as having a regulator 20 controlling a shunt circuit for the resistor. The regulator 20 comprises an electromagnet 21 having an E-shaped magnetizable core 22, upon the central leg of which is wound the energizing coil 23 connected in shunt to the load brushes 6. A movable armature 24 is pivoted at 25 to one leg of the core member 23 and has a spring 26 co-operating therewith for biasing the armature to one position. The armature 24 controls contact members 27 included in the shunt circuit about the resistor 8. The core 28 of a second electromagnet 29 is mounted upon the magnetizable core 22, and has an energizing coil 31 connected across the load brushes 6 through contact members 32 which are controlled by a movable armature 33, pivoted at 34 to the core 28. The movements of the armature 33 also actuate a lever 35, pivoted at 36 to a plate 37, which is secured at 38

to the magnetizable core 22. A depending magnetizable arm 39 is pivoted to the lever 35 and extends into an air gap 41 located in the magnetizable core 22.

- 5 In the operation of the system of Fig. 3, it will be noted that both the electromagnets 29 and 21 vibrate. The electromagnet 21 controls the shunt circuit for the resistor 8 in the field-magnet-winding circuit. The 10 electromagnet 29 controls the circuit to its energizing coil, thus insuring the vibratory action thereof, and also the movements of the arm 39 in the air gap 41, thereby producing 15 sufficient variations in the magnetic-flux density of the core 22 of the electromagnet 21 to insure the vibratory action thereof. Since the arm 39 is controlled by a vibratory electromagnet, the described variations 20 will occur intermittently.

Referring to Fig. 4, which illustrates a modification of the regulator 20 of Fig. 3, it has been deemed unnecessary to illustrate the generator 1, since the electrical connections of the energizing coils are the same in both figures. In Fig. 4, the regulator 20 comprises the electromagnet 21, having the magnetizable core 22, energizing coil 23 and movable armature 24, pivoted at 25, and 25 controlling contact members 27 against the action of the spring 26. The second electromagnet 29 comprises the core 28 and the movable armature 33, pivoted at 34, but the energizing coil 31 thereof is connected directly across the load brushes and vibrates with variations in voltage thereof. As in the regulator 20 of Fig. 3, the movable armature 33 actuates a lever 35, pivoted at 36, to control the movements of an arm 39 30 in the air gap 41 of the magnetizable core 22 of the main electromagnet.

No detailed statement of the operation of this regulator is deemed necessary, since it functions in the same manner as the 45 regulator 20 of Fig. 3.

Referring to Fig. 5, it has again been deemed unnecessary to illustrate the generator 1 and the associated circuits. In Fig. 5, the regulator 51, comprises an electromagnet 52, having a magnetizable core 53 and an energizing coil 54 connected in shunt to the load brushes of the regulated generator. A movable armature 55 co-operates 50 with the magnet 52 and controls contact members 56, located in the shunt circuit about the resistor in the field-magnet winding circuit of the regulated machine. The armature 55 is actuated against a spring 57. The magnetizable core 53 has an air gap 58 therein, in which a magnetizable arm 59, pivoted at 61, is adapted to be moved. A spring 62 engages the arm 59 and bears 60 upon a stud 63 to maintain the arm 59 in a predetermined normal position.

65 In the operation of the regulator of Fig.

5, the armature 55 will be vibrated in the normal manner and, at the same time, the position of the arm 59 in the air gap 58 will be varied to vary the flux density of the core member 53 and thereby insure the 70 vibratory action of the electromagnet 52, in the manner set forth with reference to the systems of Figs. 1 and 3.

It will be understood that the principles set forth herein may be applied to other 75 types of vibratory regulators and, hence, modifications in the system and arrangement and location of parts may be made within the spirit and scope of my invention, and such modifications are intended to be 80 covered by the appended claims.

I claim as my invention:—

1. In a voltage regulator, the combination with a magnetizable core, an energizing coil, a movable armature operated thereby, contact members controlled by said armature, and means for biasing said armature to one position, of means for intermittently varying the magnetic-flux density of 90 said core member.

2. In a voltage regulator, the combination with a magnetizable core, an energizing coil and contact members controlled thereby, of means for automatically and intermittently varying the flux density of 95 said core.

3. In a voltage regulator, the combination with a magnetizable core of substantially E-shape, an energizing coil mounted thereupon, an armature pivoted to said core and operated by said coil, contact members controlled by the operation of said armature, and a spring co-operating with said armature, of means for intermittently varying the density of the magnetic flux traversing 100 said core member.

4. In a regulator system, the combination with a dynamo-electric machine having a regulator associated therewith, said regulator comprising a magnetizable core having an air gap therein, an energizing coil, a movable armature operated thereby, contact members controlled by said armature and means for normally biasing said armature to one position, of means controlled by 110 said dynamo-electric machine for varying the magnetic field in said air gap.

5. In a regulator system, the combination with a dynamo-electric machine having a regulator associated therewith, said regulator comprising a magnetizable core having an air gap therein, an energizing coil and contact members controlled thereby, of means controlled by said dynamo-electric machine for varying the magnetic field in 120 said air gap.

6. In a regulator system, the combination with a dynamo-electric machine having a regulator associated therewith, said regulator comprising a magnetizable core 130

and an energizing coil, of means controlled by said dynamo-electric machine for varying the flux density of said core.

7. In a regulator system, the combination with a dynamo-electric machine having a resistor in circuit therewith and a regulator for controlling the effective value of said resistor, said regulator comprising a magnetizable core having an air gap therein, an energizing coil, an armature co-operating therewith and contact members controlled by said armature, of means controlled by said dynamo-electric machine for varying the magnetic field in said air gap.

15 8. In a regulator system, the combination with a dynamo-electric machine having an armature and a field-magnet winding, of regulating means therefor comprising a magnetizable core having an air gap therein, an energizing coil, an armature co-operating therewith, contact members controlled by said electromagnet armature, means for biasing said electromagnet armature to one position and means governed from said machine armature for varying the magnetic field in said air gap.

9. In a regulator system, the combination with a dynamo-electric machine having an armature and a field-magnet winding, of regulating means therefor comprising a magnetizable core having an air gap therein, contact members controlled thereby and means governed from said armature for varying the magnetic field in said air gap.

35 10. In a regulator system, the combination with a dynamo-electric machine having an armature and a field-magnet winding, of regulating means therefor comprising a magnetizable core, an energizing coil, and means governed from said armature for varying the flux density of said core.

11. In a regulator system, the combination with a dynamo-electric machine having an armature and a field-magnet winding, of regulating means therefor comprising a magnetizable core having an air gap therein, an energizing coil and intermittently operating means for varying the magnetic field in said air gap.

50 12. In a regulator system, the combination with a dynamo-electric machine having an armature and a field-magnet winding, of regulating means therefor comprising a magnetizable core, an energizing coil and intermittently operating means for varying the flux density of said core.

60 13. In a regulator system, the combination with a dynamo-electric machine having an armature and a field-magnet winding, of regulating means therefor comprising a magnetizable core, an energizing coil and intermittently operating means governed from said armature for varying the flux density of said core.

65 14. In a regulator system, the combination

with a dynamo-electric machine having an armature and a field-magnet winding, of regulating means therefor comprising a magnetizable core having an air gap therein, an energizing coil and means operated by said machine and adapted to vary said air gap.

70 15. In a regulator system, the combination with a dynamo-electric machine having an armature winding and a field-magnet winding, of regulating means therefor comprising a magnetizable core having an air gap therein, an energizing coil therefor, a movable armature co-operating therewith, contact members controlled by said electromagnet armature, a vibratory electromagnet associated therewith and having an energizing coil, a movable armature and contact members controlled thereby and a pivoted lever also controlled by said last-mentioned armature, said lever having a depending arm extending into said air gap and moved therein by said lever.

75 16. In a regulator system, the combination with a dynamo-electric machine having an armature winding and a field-magnet winding, of regulating means therefor comprising an electromagnet having a magnetizable core, an air gap therein, and an energizing coil for said core; and a second electromagnet having an energizing coil, a movable armature and a pivoted lever controlled by said electromagnet armature, said lever having a depending arm extending into said air gap and moved therein by said electromagnet armature.

80 17. In a regulator system, the combination with a dynamo-electric machine having an armature winding and a field-magnet winding, of regulating means therefor comprising an electromagnet having a magnetizable core, an air gap therein and an energizing coil for said core; a second electromagnet having a movable armature; a pivoted lever controlled by said movable armature and an arm extending into said air gap and actuated by said lever.

85 18. In a regulator system, the combination with a dynamo-electric machine having an armature winding and a field-magnet winding, of regulating means therefor comprising a magnetizable core having an air gap therein and an energizing coil therefor, an electromagnet having a movable armature and means controlled thereby for varying said air gap.

90 19. In a regulator system, the combination with a dynamo-electric machine having an armature winding and a field-magnet winding, of regulating means therefor comprising an electromagnet having a magnetizable core, said core having an air gap therein, a second electromagnet connected in parallel relation with said first-mentioned electromagnet, a movable armature co-operating

125

130

with said second electromagnet, a pivoted lever governed by movements of said armature, and means controlled by said lever and extending into said air gap whereby movements of said electromagnet armature will vary the magnetic field in said air gap to insure vibratory action of the first-mentioned electromagnet.

20. In a regulator system, the combination with a dynamo-electric machine having an armature and a field-magnet winding, of regulating means therefor comprising a plu-

rality of electromagnets connected in parallel relation, a magnetizable core associated therewith and having an air gap therein and means governed by one of said electromagnets and having other means co-operating therewith for varying the flux density of said core.

In testimony whereof, I have hereunto subscribed my name this thirteenth day of September 1921.

HAROLD A. MAXFIELD.
